HERMAN L. HARTENSTEIN, OF CONSTANTINE, MICHIGAN, ASSIGNOR TO ELECTRO CHEMICAL & DEVELOPMENT CO., OF PIERRE, SOUTH DAKOTA, A CORPORATION OF SOUTH DAKOTA.

METHOD OF MANUFACTURING IRON.

No. 889,125.

Specification of Letters Patent.

Patented May 26, 1908.

Original application filed March 9, 1907, Serial No. 361,632. Divided and this application filed July 19, 1907.
Serial No. 384,568.

To all whom it may concern:

Be it known that I, HERMAN L. HARTENSTEIN, a citizen of the United States, residing at Constantine, in the county of St. Joseph and State of Michigan, have invented certain new and useful Improvements in the Method of Manufacturing Iron, of which the following is a full, clear, and exact specification.

10 This invention relates to improvements in the manufacture of iron, and has more especial reference to the utilization of certain waste products heretofore occurring in that industry.

15 At the present time the greater portion or a large percentage of the iron ore used in the manufacture of iron is of the softer natures, such as the Mesaba ore, and which, owing to its tendency to crumble and to other 20 peculiarities of structure, is reduced in great part during handling and crushing to a very fine state of subdivision. When the furnace is subjected to the necessary high pressure for successfully blowing it a large percentage 25 of this fine ore or material is blown out of the smelter and in fact cannot be retained therein, but is caught or settles in the dust chamber, from which it is removed at intervals. The value of the fine material thus ejected 30 from a furnace is quite a desideratum, as it amounts to from five to ten per cent. of the entire quantity of ore placed in the blast furnace. Heretofore unsuccessful efforts have been made to recover and utilize this 35 waste, but as they consist mainly in attempts to form the waste into bricks or blocks by compressing it with binders or adhesives and then drying or baking the blocks, which are afterwards charged into the furnace with the 40 other ore, fuel and fluxing materials, it is obvious that these prior methods add so greatly to the expense of the final product as to make them of but little value. As a consequence, manufacturers generally re- 45 gard this fine ore which discharges from the furnace as a total waste and remove it and discard it with as small an expenditure of time and labor as possible. It is also well known that in the manufacture of iron where 50 blast furnaces are employed which use solid fuel such as coal and coke, a large amount of the coal and coke, and particularly the coke, which is delivered to them for use is a total

waste, so far as a fuel for blast furnaces is concerned, because of its comminuted or 55 pulverized condition and the tendency of such fine fuel to bridge in the furnace and seriously interfere with the proper operation thereof and the consequent reduction in its output. This fine fuel, therefore, is also 60 discarded like the dust or fine particles of ore which are carried off in the blowing operation.

The object of my present invention, therefore, is to utilize all or any of these waste materials, and to produce therefrom a valuable grade of iron at minimum cost.

With these ends in view, the invention consists in the features of novelty which will now be described more fully and with reference to the accompanying drawings, showing 70 a suitable apparatus for carrying the method into effect, and will then be particularly pointed out in the claims.

In the said drawings,—Figure 1 is a diagrammatic illustration of an apparatus utilized in the performance of this method, showing the apparatus in side elevation. Fig. 2 is an enlarged detail view partly in section of a portion of a conveyer hereinafter described. Fig. 3 is a diagrammatic plan view of the apparatus, and Fig. 4 is a vertical longitudinal sectional view of one end of the rotating furnace on an enlarged scale.

In carrying out the invention, I mix from 500 to 700 pounds, approximately speaking, 85 of the waste coal or coke before referred to to every ton of metallic iron contained in the flue dust, which as is understood, is the fine ore that discharges from the furnace without being converted, the amount of metallic iron 90 in such dust being of course ascertained by proper analysis. This mixture of fuel and flue dust is then fed into a suitable furnace, where it is subjected to sufficient heat to cause the carbon of the carbonaceous material or fuel to combine with the oxygen of the flue dust, thereby resulting in a good grade 95 of iron which is in the form of sponge. This iron sponge may be utilized in the manufacture of iron and steel and in open hearth 100 puddling, electric, Bessemer, or any other steel or iron manufacturing processes according to the usual methods now followed. It is preferable, of course, to thus utilize the iron sponge while it is in a highly heated condition so that the heat thereof may not be 105

wasted and the resultant iron or steel in the production of which the sponge was utilized may be cheapened, yet if desired the sponge may be withdrawn from the furnace and permitted to cool and then transported to places where required for use in the manufacture of other products, but in the event it be allowed to cool before it is thus used it should be converted into blooms, slabs, billets, or 10 other solid forms by passing it between rolls, screw bars, or hammers while it is still heated to prevent oxidation which readily occurs when exposed to the atmosphere. It is, of course, obvious also that while my present 15 invention is primarily designed for the utilization of the heretofore waste products before referred to, iron ore mixed with carbonaceous material such as described if reduced to this fine state even artificially, may 20 be economically and advantageously converted into metallic iron by my described process, as will hereinafter more fully appear.

Referring to the apparatus, 1 is a rotary kiln such as might be employed in calcining 25 limestone, and which is supported on suitable bearings 2, 3; and provided with a gear 4, capable of being driven by a pinion 5 on shaft 6 from any suitable source of power. At the lower end of the rotary cylinder 1 is 30 arranged a fixed or non-rotary hearth 7, which serves as a combustion chamber, and into one end of which leads a pipe 8 for gas or other suitable fuel. Between the contiguous ends of the cylinder 1 and the hearth 35 7 is a housing 9, which is fitted accurately to both but is stationary and receives from the cylinder 1 as it rotates the iron sponge produced therein by the action of the heat generator in the combustion chamber 7 upon 40 the mixture of iron ore and coal or coke in the cylinder 1. This housing 9 has a discharge aperture 10 in its bottom, through which the iron sponge falls as it arrives at that point. If the sponge is to be introduced 45 immediately into a furnace and used in the production of iron or steel as heretofore mentioned, it may be received in a hopper 11 as it falls through the discharge opening 10, and discharged from time to time into cars 50 12 or other receptacles and conducted directly to the furnace in which it is to be used. In this example of the apparatus I have shown such a furnace in the form of an electric furnace 13 of the usual or any suitable 55 type, the construction of which is well understood and need not be described in detail. In the production of pig iron in such a furnace a large quantity of gas is evolved and this is utilized in heating the iron ore and 60 carbonaceous material in the cylinder 1, by conducting it from the electric furnace through any suitable flue or flues 14, 15, 16 back to the inlet pipe 8 of combustion chamber 7. This inlet pipe 8, if desired, may also

lead directly from any suitable gas producer 65 17 for supplying the combustion chamber 7, should the gas from the electric furnace be insufficient. The electric furnace is shown with a stack 18, having a damper or valve 19, so that if desired the gases may be allowed 70 to discharge directly into the atmosphere. The flue 14, 15, is shown with an exhauster 20 to assist in drawing the gases from the electric furnace and forcing them into the combustion chamber 7. 75

The mixture of ore and coke or coal may be fed into the upper end of the rotating cylinder 1 by any suitable means directly, if desired, or they may be passed through any suitable preheating device, as, for example, a substantially horizontal passage or chamber 21, in which is arranged an endless conveyer 22 driven continuously, or as desired, by any suitable means and discharging into the upper end of the cylinder 85 1, from which the waste gases and heat rise 1, from which the waste gases and heat rise into the chamber 21 and surround and heat the material progressing gradually to the inlet of the cylinder 1 on the conveyer 22.

According to the usual methods of manufacturing pig iron in blast furnaces, from 2,000 to 2,500 pounds of a good grade of coke and about 1200 pounds of limestone are required for every ton of iron manufactured, while by means of my improved 90 method the same result may be accomplished by the use of this waste product, *i. e.*, coal dust or coke dust, and about only one-fourth in quantity of that is required, and the limestone heretofore required is entirely 100 unnecessary, although a small quantity for fluxing purposes might be used if desired without increasing the expense. It is apparent, however, that a flux is not essential when proceeding according to my method, 105 since there does not exist in my method the necessity for reducing the material to a molten condition, while that condition is essential in the production of iron in an ordinary blast furnace because otherwise the 110 product could not be successfully withdrawn. It is also obvious that my described method reduces the cost of production in the matter of labor, since the operation is performed by mechanical means and 115 the material is advanced automatically from its crude state to a state of sponge ready for use in the electric or other furnace without handling.

This application is a division of my application Serial No. 361,632, filed March 9th, 1907, containing claims to the method of making iron by the treatment of comminuted ore and carbonaceous material.

Having thus described my invention, 120 what I claim as new therein and desire to secure by Letters Patent, is:—

The herein described method in the manu-

facture of iron which consists in forming a mixture of flue dust and comminuted carbonaceous material, subjecting the same to a reducing degree of heat to produce iron sponge, and finally compressing such sponge.

In testimony whereof I have signed my name to this specification, in the presence of

two subscribing witnesses, on this eighth day of July A. D. 1907.
